UNITED STATES PATENT OFFICE.

JAMES JENKS, OF DETROIT, MICHIGAN.

FEED-WATER INJECTOR.

SPECIFICATION forming part of Letters Patent No. 242,652, dated June 7, 1881.

Application filed October 23, 1880. (No model.)

To all whom it may concern:

Be it known that I, JAMES JENKS, of Detroit, in the county of Wayne and State of Michigan, have invented an Improvement in Feed-Water Injectors, of which the following is a specification.

My invention relates to improvements in that class of feed-water injectors in which the impurities in the boiler are prevented from entering the feed-water injector and interfering with its operation by means of a screen or strainer secured within the steam-pipe which connects the boiler and injector.

The invention consists in the peculiar construction and arrangement of the coupling and parts connected therewith, by means of which the screen may be inserted or removed and held in place, as hereinafter more fully set forth, and pointed out in the claim.

In the accompanying drawings, which form a part of this specification, there is shown a view of a feed-water heater such as is described in my application for a patent which was allowed September 13, 1880, and wherein F represents the steam-pipe which is designed to connect the boiler and injector. As it frequently occurs that impurities from the boiler are forced by the steam into the interior of the injector, (or from the interior of the intercommunicating pipe,) which materially affect and sometimes prevent the operation of such injector, I secure within the pipe F, preferably near the body or operating parts of such injector, a screen, S, preferably of wire-gauze of sufficient fineness of mesh as not to interfere with the free passage of steam, whereby all impurities are prevented from entering the injector.

The wire-gauze screen S is secured in position in the pipe F in the following manner: 40

a represents an interiorly screw-threaded coupling, which forms a part of the injector. b represents a coupling, screw-threaded exteriorly near its lower end to engage with the interior screw-threads of the coupling a. The coupling b is bent outwardly near its middle to form an interior shoulder or seat, c, for the outer frame of the screen S to rest on when in position in the pipe F; and the coupling b is also interiorly screw-threaded near its upper end, to engage with the screw-threaded end of the pipe F, provided with a shoulder, e, bearing against the upper edge of the coupling b. By means of this construction the wire-gauze screen can readily be inserted and removed and held securely in place.

I am aware that strainers have heretofore been employed in the steam and water pipes leading to an injector, as shown in Letters Patent granted to W. H. Newell, dated June 12, 1877, No. 191,773, and I therefore lay no claim broadly, to such invention.

What I claim as my invention is—

The combination, in an injector, of the interiorly screw-threaded coupling a with the coupling b, screw-threaded interiorly near its upper end and exteriorly near its lower end, and having the shoulder or seat c, pipe F, exteriorly screw-threaded near its end and provided with the shoulder e, and wire-gauze screen S, substantially as described, and for the purpose set forth.

JAMES JENKS
